UNITED STATES PATENT OFFICE.

MAX A. SKALL, OF NEW YORK, N. Y.

DESIGN FOR A WHISK-BROOM HOLDER.

SPECIFICATION forming part of Design No. 36,430, dated July 14, 1903.

Application filed January 27, 1903. Serial No. 140,813. Term of patent 3½ years.

To all whom it may concern:

Be it known that I, MAX A. SKALL, a citizen of the United States, and a resident of the city of New York, borough of Manhattan, in the county and State of New York, have invented a new, original, and ornamental Design for a Whisk-Broom Holder.

Reference is to be had to the accompanying drawings, forming a part of this specification, in which—

Figure 1 is a front perspective view, and Fig. 2 is a rear perspective view, of a whisk-broom holder embodying my design.

I claim as new and desire to secure by Letters Patent—

The ornamental design for a whisk-broom holder herein shown.

In testimony whereof I have signed my name to this specification in the presence of two subscribing witnesses.

MAX A. SKALL.
